UNITED STATES PATENT OFFICE.

JOHN EDWARD OGDEN, OF CORNWALL, NEW YORK, AND CHARLES C. TOMKINSON, OF PLAINFIELD, NEW JERSEY; SAID TOMKINSON ASSIGNOR TO SAID OGDEN.

STRUT-DOOR.

1,274,439.

Specification of Letters Patent. Patented Aug. 6, 1918.

Original application filed October 30, 1917, Serial No. 199,276. Divided and this application filed May 23, 1918. Serial No. 236,116.

To all whom it may concern:

Be it known that we, JOHN EDWARD OGDEN, a citizen of the United States of America, and a resident of Mountainville, town 5 of Cornwall, Orange county, and State of New York, and CHARLES C. TOMKINSON, a citizen of the United States of America, and a resident of Plainfield, Union county, and State of New Jersey, have invented certain 10 new and useful Improvements in Strut-Doors, of which the following is a specification, reference being had to the accompanying drawings, forming a part thereof.

This invention relates to new and useful 15 improvements in doors and especially to large heavy doors such as are used on pier sheds, warehouses and the like, and is related more specifically to two-section doors.

One object is to provide struts for supporting the door in certain of its open positions and automatically actuated mechanism for moving the struts into the desired supporting relation with the other parts of the apparatus.

Another object is to provide a simple but strong operating mechanism for such doors which is so arranged that the door is amply supported in all of its positions.

In order that our invention may be thoroughly understood we will now proceed to describe the same in the following specification, and will then point out the novel features thereof in appended claims.

Referring to the drawings:

Figure 1 is a sectional side elevation of a door made according to and embodying this invention, with the parts shown in the positions they assume when the door is closed.

Fig. 2 is a similar view of the same parts with the door fully open.

Like characters of reference designate corresponding parts in all the figures.

10 designates the side posts and 11 the 45 lintel of a door opening. This is closed by a door which comprises an upper section 12, and a lower section 13. At the sides of the upper section are guides 14 up into which the lower section slides. Guide rollers 15 50 are provided at the lower corners of the lower door section, which run upon the door posts 10. Hoisting chains 40 are also connected with these lower corners of the lower door section as for example to the pivots

of the guide rollers 15. These chains run 55 up over sheaves 17 on a shaft 18 above the door opening and down under sheaves 41 on counterweights 42 and up to fixed anchorages 43.

Pivoted to brackets 20 which are affixed 60 to the sides of the upper door section, are struts 21. Pivots 22 at the lower end of the struts support rollers 23 which run between vertical guides 25. Ropes 44 connected with these lower ends of the struts run up to and 65 over sheaves 45—46 and down to a counterweight 47.

On the shaft 18 is a gear 50 and a rotative arm 51. A gear 52 mounted on this arm is in mesh with gear 50 and 53 is a gear connected with sheave 45, 54 is a pivoted lever connected with the arm 51 by a rod 55. This is provided with a forked portion 56 and a spring 57 is connected therewith and to a fixed point 58, as shown, and 59 is a bracket 70 projecting above the lower door section for actuating the lever 55. A shelf bracket 60 is shown in Fig. 2 for supporting the parts of the door sections in their open 75 position, in which they overhang their pivotal connections with the struts. 80

When the shaft 18 and sheaves 17 are rotated to raise the hoisting ropes 40, the lower door section will be raised in the guides 14 to a position back of the upper door section 85 12. When the lower door section reaches the upper end of its vertical movement, the bracket 59 will engage the forked portion 56 of lever 54 and raise it and the arm 51. The spring 57 will complete this movement 90 until gear 52 is brought in mesh with gear 53. The rotation of shaft 18 through the gears described will now be imparted to sheave 45 which will cause the ropes 44 to raise and support the lower ends of the 95 struts during the remainder of the opening movement and support the struts while the door is open.

In closing, the gears remain in mesh and the struts are lowered until the bracket 59 100 engages the forked part 56 of lever 57 and pulls it down, which movement is completed by the action of the spring 54.

This application is a division of an application filed by us October 30, 1917, and 105 given Serial No. 199,276.

What we claim is:

1. A door comprising an upper section

- and a lower section, guide connections between the sections to provide for the lower section being raised up beside the upper section, downwardly extending struts having their upper ends pivotally connected with the sides of the upper section above its lower edge, hoisting means, connections therefrom to the lower corners of the lower door section, whereby the lower section may be first raised vertically beside the upper section and thereafter the lower edges of both sections may be raised together vertically, permitting the other portions of the sections to swing out of the vertical plane, hoisting means for the lower ends of the struts, and means actuated by the vertical movement of the lower section for connecting the strut hoisting means with the door hoisting means.
- 5 10 15 20 25 30 35 40 45 50 55 60 65 70 75 80 85 90 95
5. A door comprising an upper section and a lower section, guide connections between the sections to provide for the lower section being raised up beside the upper section, downwardly extending struts having their upper ends pivotally connected with the sides of the upper section above its lower edge, a hoisting shaft, connections therefrom to the lower corners of the lower door section, whereby the lower section may be first raised vertically beside the upper section and thereafter the lower edges of both sections may be raised together vertically, permitting the other portions of the sections to swing out of the vertical plane, hoisting means for the struts comprising sheaves, and flexible elements connected with the lower ends of the struts and running over said sheaves, reduction gearing between said sheaves and the hoisting shaft, and means actuated by the movements of the door sections for connecting and disconnecting said gearing.
4. A door comprising an upper section and a lower section, guide connections between the sections to provide for the lower section being raised up beside the upper section, downwardly extending struts having their upper ends pivotally connected with the sides of the upper section above its lower edge, a hoisting shaft, connections therefrom to the lower corners of the lower door section, whereby the lower section may be first raised vertically beside the upper section and thereafter the lower edges of both sections may be raised together vertically, permitting the other portions of the sections to swing out of the vertical plane, hoisting means for the struts comprising sheaves, and flexible elements connected with the lower ends of the struts and running over said sheaves, a gear on the hoisting shaft, a gear connected with said sheaves, an intermediate gear, a movable support therefor, and means on the lower door for causing the movement of said lower door section to move said gear support to bring the intermediate gear into or out of mesh with said other gears.
- In witness whereof we have hereunto set our hands this 21st day of May, 1918.
- J. EDWARD OGDEN.
CHARLES C. TOMKINSON.
- Witness:
I. B. MOORE.
